STANCHION FOR BEVERAGE TAP

Daniel J. Oelschlaeger, Oak Creek, Wis., assignor to Display Corporation International, Milwaukee, Wis.

Filed Apr. 7, 1972, Ser. No. 242,275

Term of patent 14 years

Int. Cl. D15—08

U.S. Cl. D94—3 A

FIG. 1 is a front elevation of a stanchion for beverage tap showing my design;

FIG. 2 is a side elevational view;

FIG. 3 is a rear elevational view; and

FIG. 4 is a top plan view.

I claim:

The ornamental design for a stanchion for beverage tap, as shown.
